UNITED STATES PATENT OFFICE.

RAYMOND F. MUDD, OF CHICAGO, ILLINOIS, ASSIGNOR OF ONE-HALF TO JOSEPH A. MUDD, OF CHICAGO, ILLINOIS.

LOCK FOR AUTOMOBILES

1,170,987.

Specification of Letters Patent.

Patented Feb. 8, 1916.

Application filed September 19, 1914. Serial No. 862,486.

To all whom it may concern:

Be it known that I, RAYMOND F. MUDD, a citizen of the United States, residing at Chicago, in the county of Cook and State 5 of Illinois, have invented a new and useful Improvement in Locks for Automobiles, of which the following is a specification.

My invention relates to locking-means for automobiles, and more particularly to a 10 form of lock adapted for application to the steering-gear.

The object of my invention is to provide a steering-gear lock which may be readily applied to existing forms of steering-gear 15 in such a manner as to be proof against removal when in the locked position.

Further objects and advantages of the invention will appear from the following detailed description of a preferred embodiment 20 of the same. In this description reference will be had to the accompanying drawings, in which:

Figure 1 is a cross-sectional elevation of 25 steering-wheel and a portion of the steering-column of an automobile, my locking-means being shown in position thereon; Fig. 2 is a detail plan view of the locking-means proper shown substantially as on the line 2-2 of Fig. 1; Fig. 3 is a lower plan 30 view of the locking-means substantially on the line 3-3 of Fig. 1; Fig. 4 is a detail view of that portion of the lock attached to the rim of the steering-wheel, one of the plates being partly broken away; Fig. 5 is a 35 detail view of the upper end of the locking-arm; Fig. 6 is a detail sectional view, taken on the line 6 of Fig. 3; Fig. 7 is a face view of the steering-column clamp, taken substantially on the line 7 of Fig. 8, 40 and Fig. 8 is a cross-sectional view to the locking-arm and clamp taken on the line 8 of Fig. 1.

Referring to Fig. 1, there is shown a 45 steering-column 10 of a well-known form, carrying at its upper end the steering-wheel, generally designated by 11 and comprising a spider 12 which actuates the steering-shaft 13 and a rim-portion 14 fastened to the arms of the spider as by screws 50 15. The engine control-means which comprises the usual quadrants and levers is mounted on the steering-column directly beneath the wheel and indicated, generally, by 16.

55 In applying my invention to steering-

gear of this well-known type, I provide clamp-sections 17 and 18 (see Fig. 8), so formed as to bear upon and embrace the outer face of the elliptical steering-column 10 and to be clamped thereto, as by screws 60 19, the heads of which are countersunk in the outer face of the clamp-section 18. The lower end of this clamp-section has formed integrally therewith the lugs or knuckles 20, and hinged to these knuckles, as by a pintle 65 21, is a locking-arm 22. By reference to Fig. 1 it will be seen that this arm is angular in form, the hinged lower end 23 thereof being bent so as to lie flush with the face of the clamp-section 18 when the arm 70 proper is in the position shown in Fig. 1. It will be apparent that in this position of the parts the heads of the screws 19, by which the clamp-sections 17 and 18 are secured to the column, are completely masked 75 by the end 23 of the arm so that it is impossible to loosen or remove the clamp when the arm is in the position shown in Fig. 1.

The upper end of the locking-arm 22 is rabbed out as shown at 24 in Fig. 5 to 80 form an arcuate lip 25 which lies over and bears against a lip 26 formed integrally with the steering-wheel clamp-section 27. This section forms half of a steering-wheel clamp, indicated, generally, by 28. The 85 conjugate member 29 of the clamp is lap-jointed to form an interlock, as shown at 30, in Figs. 1 and 6, to lock securely to this section 27. The inside edge of the clamp-section 29 is slotted, as at 30, to straddle the 90 spider-arm 31, this edge being provided with a lip 32 with which the upper face of the locking-arm 22 engages. The clamp-sections 27 and 29 are secured in place on the rim of the steering-wheel with locking-screws 33, and the lips 26 and 32 are spaced apart by lugs 34 formed on the inner face of the lip 32 adjacent its ends, as shown in Fig. 4. The locking-screws 33 are countersunk similarly to the screws 19, and in the 100 position of the arm shown in Fig. 1 these screws are completely masked by the lip 25 of the locking-arm. The steering-rim clamp-member, as well as the column-clamp-member, is, therefore, completely secured 105 against being loosened or detached, so long as the locking-arm 22 is in the operative position shown in Fig. 1. To maintain the locking-arm in this position, I provide a lock 35, shown as of rectangular form and 110

let into a recess 36 in the upper face of the locking-arm 22 so as to lie flush therewith. The lock 35 may be of any suitable construction, it being essential merely that it be provided with a bolt, as shown at 37, which shall enter and engage the recess 38 formed in a lug 38' on the clamp-section 27 and being within the slotted end of the clamp-section 29. The lock 35 will preferably be riveted in place in the recess of the arm 22, as by the rivets 39, so as to be secured against removal by any ordinary means.

From Fig. 1 it will further be noted that the clamp-section 27 is recessed, as at 40, to receive the extremity 41 of the spider-arm 31, and this recessed-portion of the clamp section 27 masks the head of the screw 15 by which a spider-arm is secured to the rim of the steering-wheel. The key aperture 42 of the lock 35 will preferably be offset from the center of the lock so that a key may be inserted from the top without interference by the spider-arm 31.

As an additional security, and to relieve, in so far as possible, the hinge pintle 21 and the lock-bolt 27 from any strains which they might receive, if it were attempted to break the locking-means by rotating the steering-wheel, I provide the locking-arm 22 with two sets of inclined lugs, the lower set comprising the backwardly-hooked rectangular lugs 43 which enter apertures 44 in the outer face of the clamp-section 18 (see Fig. 8), and the upper set comprising the backwardly-hooked rectangular lugs 45 formed on the inner face of the lip 25 and engaging apertures 46 in the lip 26 of the rim clamp-section 27 (see Fig. 6). It will be noted that the lugs 45 will carry all strains which would be imposed upon the lock-bolt 37 by an attempt to turn the steering-wheel, while the lower lugs 43 protect the hinge pintle 21 from the same strains, and, in addition, will act to retain the lower end 23 of the locking-arm in position, even though the hinge pintle be driven out. Thus it will be clear from Fig. 1 that, so long as the upper end of the locking-arm remains secured to the rim of the steering-wheel, it will be impossible to pry or otherwise force out the lower end of the locking-arm without breaking the lugs 43. The provision of these two sets of lugs is an important feature of my invention, inasmuch as it would be difficult to provide a hinge or a locking-bolt which would be strong enough to resist the enormous strains which would be set up by a strong pull on the rim of the steering-wheel. By my construction the lock-bolt 37 can be broken only by a direct downward push upon the locking-arm 22 while the hinge pintle 21 cannot be stressed, except by prying the lower end of the locking-arm directly outward.

In the unlocked position of the parts, the

arm 22 will be swung downwardly on its hinge until it lies parallel with the column 10, and I preferably provide a spring-catch 47 secured as by a light clamp band 48 to retain the arm 22 in its downwardly-swung position and to prevent it from rattling or swinging.

It will be seen that the locking-means, above described, may be readily secured to a steering-gear of the type illustrated without alteration of the steering-gear and without defacing the same, all securing-means forming a part of the locking-device itself, so that the same may be applied by any person of ordinary intelligence and without any tools, excepting a screw-driver. It will further be seen that in the locked position of the parts the securing-screws of all parts are completely masked, so that it is impossible to detach the locking-device by any other means than by breaking some portion thereof.

The steering-wheel rim-clamp 28 may be applied at any part of the periphery of the steering-wheel, but I preferably so locate this clamp that it will register with the locking-arm 22 only when the steering-wheels of the automobile have been canted to an acute angle. This renders the locking-means much more efficient in that it is wholly impossible to move the car except in a circle. If desired, however, the clamp 28 may be applied in such position as to permit the wheels to be locked in the straightforward relation, this being entirely at the option of the person who attaches the lock.

While I have shown and described in considerable detail a form of locking-means adapted for application to a particular type of steering-wheel, it is to be understood that such showing and description is illustrative only, and that while the preferred embodiment of the invention illustrated includes many structural advantages, I do not regard my invention as limited to these particular constructions, except in so far as such limitations are included within the terms of the appended claims, in which it is my intention to cover all the patentable novelty inherent in my invention in view of the prior art.

What I claim as new and desire to secure by Letters Patent is:

1. In a device of the class described, a clamp adapted to be secured to a steering-column, an arm hinged to the clamp at one end, a two-piece clamp adapted to embrace the rim of a steering-wheel and to straddle a spider arm of the same, and means for locking the free end of said hinged arm to said steering-wheel clamp.

2. In a device of the class described, a clamp adapted to be secured to a steering-column, an arm hinged to the clamp at one end, a locking-bolt mounted in the free end

of the arm, means for advancing and retracting the bolt, and a two-piece clamp adapted to embrace the rim of a steering-wheel and to straddle a spider arm thereof, 5 said clamp having a recess to receive the locking-bolt.

3. In a device of the class described, a clamp adapted to embrace a steering-column, detachable fastening means to secure 10 said clamp in a fixed position on the column, an arm hinged at one end to the clamp, a two-piece clamp adapted to embrace the rim of a steering-wheel, detachable fastening means for securing said clamp to said rim, 15 and means for locking the free end of said arm to said steering-wheel, said arm masking both of said fastening means when in the locked position.

4. In a device of the class described, a 20 clamp-section adapted to embrace one side of a steering-column, a conjugate clamp-section adapted to embrace the opposite side of the column, securing-screws seating in the outer face of said second clamp-section and 25 engaging said first clamp-section, an arm hinged to the lower edge of said second clamp-section and adapted to swing upwardly to lie over the face thereof and mask the said screws, and means for locking the 30 free end of said arm to a steering-wheel.

5. In a device of the class described, a clamp-section adapted to embrace one side of a steering-column, a conjugate clamp-section adapted to embrace the opposite side 35 of the column, securing-screws seating in the outer face of said second clamp-section and engaging said first clamp-section, an angular arm hinged to the lower edge of said second clamp-section and adapted to swing 40 upwardly to lie over the face thereof and mask the said screws, a clamp-section adapted to embrace one side of the rim of a steering-wheel, a conjugate clamp-section adapted 45 to embrace the opposite side of the rim, securing-screws seated in the outer face of said second clamp-section and engaging said

first clamp-section, a locking-bolt mounted in the free end of said arm and adapted to engage a recess formed in said rim clamp-section, and a lip formed on the free end of 50 said arm and adapted to overlie and mask the securing-screws of said rim clamp-sections when the parts are in the locked position.

6. In a device of the class described, a 55 clamp adapted to be secured to a steering-column, an angular arm hinged at one end to the lower edge of said clamp, backwardly-hooked lugs carried by the inner face of said arm and adapted to enter recesses in the 60 outer face of said clamp, and means carried by the outer end of said arm to lock the same to a steering-wheel, whereby in the locked position of the parts said lugs are maintained in engagement with said recesses. 65

7. In a device of the class described, a clamp adapted to embrace a steering-column, an arm hinged to the clamp at one end, a clamp-section adapted to embrace the rim of a steering-wheel, said clamp-section being 70 slotted to straddle a spider-arm of the wheel, a lock mounted in the free end of said arm, and a locking-bolt, said lock including a bolt-member adapted to enter a recess in said steering-wheel clamp-section. 75

8. In a device of the class described, a clamp adapted to be secured to a steering-column, an arm hinged to the clamp at one end, a clamp adapted to be secured to the rim of a steering-wheel, means for locking 80 the free end of said hinged arm to said steering-wheel clamp, lugs carried by said arm and engaging recesses in said steering-column clamp in the locked position of the parts, and lugs carried by said arm and 85 adapted to engage said steering-wheel clamp in the locked position of the parts, substantially as and for the purposes described.

RAYMOND F. MUDD.

In presence of—

A. C. FISCHER,
N. B. DEARBORN.
